7 Claims. (Cl. 19—159)

This invention relates to a coiler gear mechanism for 10 guiding a sliver into a sliver can.

In placing a sliver in a sliver can, it is possible to accommodate the maximum amount of sliver in a can having a given volume by providing a mechanism adapted to lay the sliver along circular loci and means to gradually change the position at which the sliver is laid down along the circular loci.

In order to attain the above mentioned object, it is usual to feed the sliver to the center of a coiler gear from above to deliver it through a hole situated near the outer periphery of said coiler gear. Usually a tube is utilized to guide the sliver while it is passing through the coiler gear.

The number of revolutions of the coiler gear is determined by the diameter of a circle along which the sliver is laid down during one revolution of the coiler gear and the speed of the sliver. Therefore, when the coiling diameter is too small, or when the angular velocity is too fast, difficulties arise with the bearings employed, the problems increasing with the running speed.

More particularly, for low-speed operation a mechanism is used in which a circular projection is provided on the bottom surface of the coiler gear, and a circular groove receiving said projection is provided on a coiler-gear-supporting plate for providing a sliding support therebetween. A thrust bearing may be interposed between the coiler gear and its supporting plate.

For high-speed operation, three types of mechanism have been developed. In one mechanism, three or four roller units, which are carried by ball bearings on a supporting plate, are arranged at spaced points along the outer periphery of the plate so as to mount the coiler gear in a floating state with respect to the supporting plate at three or four locations via said rollers. In another mechanism, a particularly large ball bearing is utilized, the bearing having its inner race fixed to the coiler gear and its outer race to the supporting plate. In either of said mechanisms, the coiler gear is supported at its outer periphery so that the running speed of its bearing elements becomes very high which also imposes certain practical limitation.

In order to provide an efficient supporting means suitable for much higher speeds without imposing such limitation, in the above mentioned two arrangements a suitable supporting assembly such as a ball bearing is arranged at a reduced-diameter top portion of the coiler gear instead of supporting the coiler gear at its bottom portion where its diameter is maximum.

Since a coiler gear can be generally assumed to be conical, it is able to utilize a supporting surface of relatively small diameter when the coiler gear is supported at its top portion. Moreover, the necessary number of revolutions of the coiler gear itself may be the same as those in the above mentioned two mechanisms. This permits considerable reduction in the running speed of the supporting member. Furthermore, by this arrangement, also, the bottom of the coiler gear is maintained in a floating state with respect to the supporting plate.

For another reason, it is usual to provide gear teeth on the large periphery of the coiler gear and to arrange it to mesh with a driving pinion. In some cases, in lieu of gear teeth, a groove is provided to be driven by a suit-

2

able driving means such as a rope or like flexible element. While these arrangements are utilized principally in the first mentioned mechanism, gear teeth are arranged at the top portion of the coiler gear in the last mentioned mechanism. Thus, all of these driving arrangements are disposed near the supporting elements.

Considering now the force acting upon the bearing in these prior arrangements, there is a tendency for one portion of the bearing to be subjected to a larger force, at a definite portion and in a definite direction, than other portions owing to the driving means.

As is well known to those skilled in the art, since the coiler gear has a configuration which is quite unbalanced for rotation, it has a tendency to gyrate under influence of its centrifugal force. Notwithstanding these two inevitable states of forces, the coiler gear is supported by a single bearing means in these said prior arrangements.

Especially, in the last mentioned arrangement, since the coiler gear is supported at the top of a circular core, the massive portion of the gear is suspended beneath the supporting means. Accordingly, in prior coiler gear mechanism having inevitably unbalanced construction, the force acting upon its bearing caused by the gyrating motion is very large.

It is the principal object of this invention to provide a novel coiler gear mechanism which can obviate the above mentioned difficulties.

Another object of this invention is to provide an improved coiler gear mechanism which can operate at higher speeds than prior mechanisms without causing any undesirable vibration or damage to the bearing.

The feature of this invention resides in separating into two parts, i.e., a top part and a bottom part or pan, a coiler tube gear which is usually made as an integral unit and to provide separate bearings to the respective parts. By such a construction, the upper bearing, for example, functions to support the thrust caused by gear drive but is substantially free from the effect of unbalance of the coiler gear itself, and this effect of unbalance may be supported by the bearing device in the bottom part.

In another embodiment of this invention, the upper bearing is arranged to support the thrust caused by gear drive as well as the effect of unbalance in the coiler tube portion. However, in this case, as the mass of the coiler tube is relatively small, the effect of unbalance is relatively small, and this effect can be further reduced by utilizing a suitable counter weight. On the other hand, the bottom bearing device must support the bottom pan body having relatively large mass, but there is no serious problem because the pan can be constructed to have a shape easy to balance.

Generally the bottom part or pan is required not only to support relatively massive coiler gear but also to withstand large upward force acting upon its lower surface caused by groups of slivers firmly compacted in a sliver can. In addition, inasmuch as the bottom part operates at high speed, the force acting upon the lower bearing device is considerably larger than that acting upon the upper bearing device.

In accordance with this invention, however, various forces created during the operation of a coiler gear are divided so as to be independently supported by separate bearing devices, thereby reducing the loads on the bearings and providing efficient operation at even higher speeds.

It is believed that the invention will be better understood from the following description taken in connection with the accompanying drawings.

In the drawings:

FIG. 1 is a side elevational view, partly in section, of one embodiment of this invention;

FIG. 2 is a plan view illustrating the relation between a coiler pan and its supporting means, or bearing assemblies;

FIG. 3 is a side elevational view, partly in section, of the upper part of the mechanism shown in FIG. 1 for explaining a method of supporting the upper part;

FIG. 4 is a side-elevational view, partly in section, of the lower part for explaining its method of support;

FIG. 5 shows a plan view illustrating a curved, inclined guide tube;

FIG. 6 is a side elevational view, partly in section, of the upper part of a modified mechanism for explaining its method of support; and

FIG. 7 is a side elevational view, partly in section, of the bottom part of the modified mechanism for explaining its method of support.

Throughout the accompanying drawings, the same reference numerals are assigned to similar or corresponding parts.

Referring now to FIG. 1 of the accompanying drawings, after passing between a pair of calendar rollers 1 and 1a a sliver is inserted into an inlet opening A at the top of a coiler-gear mechanism and is discharged to drop into a sliver can, not shown, which is arranged beneath the mechanism, through an inclined guide passage B and a discharge opening C. The sliver is laid in a circular manner as the discharge opening sweeps along a circular locus upon the rotation of the assembly.

While any suitable means may be used for rotating the assembly, a helical-gear drive is illustrated as an example.

As above pointed out, according to this invention the coiler-gear mechanism is divided into two parts 30 and 31, the upper part 30 comprising a gear 2 fixed to the inner race of a ball bearing 10 at its upper portion, a downwardly projecting inclined guide tube 3 which is secured to the lower surface of the gear 2 to define said passage B, a vertical arm or shaft 4, and pins 5 and 6 secured to the lower end of the shaft 4 which is integral with the gear 2. The outer race of the bearing 10 is secured to a fixed block 11 which in turn is rigid with a frame 12. Thus, as shown in FIGS. 1 and 3, the top part 30 is rotatably supported in correct position by the ball bearing 10. To rotate this top part a helical pinion 14 meshing with helical-gear teeth 7 of the gear 2 is mounted on a drive shaft 13, the pinion 14 and shaft 13 constituting a drive means coupled with the upper coiler member via its gear 2.

The force acting upon the top bearing 10 is composed of a first force required to rotate the top part 30 while supporting its weight, a second force necessary to maintain the top part in its correct position against a force normally tending to bias it in a definite direction, and a third force caused by the unbalanced condition during rotation due to asymmetrical configuration of the lower portion.

With such a construction, when compared with a conventional mechanism wherein gear teeth are cut around the periphery of a coiler pan, the diameter of the pan can be made smaller, so that, even where the same gear mechanism is used, it is possible to make it have a smaller radius of gyration, thus increasing the rate of acceleration or deceleration. This means that troubles occurring in the case of operating at even higher speed are greatly minimized, thereby providing a tube gear mechanism suitable for high speed operation.

As shown in FIGS. 2 and 4, the bottom part 31 of the coiler-gear mechanism comprises a shallow disc-shaped pan 22 which is supported by four guide rollers 20, each having a ball bearing 21 (FIG. 1) and received within a groove 23 (FIG. 1) on the outer periphery of the pan. The pan is provided with holes 24 and 25 for receiving said pins or dowels 5 and 6, respectively, and the discharge opening C near its periphery. The bottom pan 22 has no gear or other driving means other than said pins

and is supported by said four rollers 20 in alignment with the upper part with the flanges of the groove 23 forming axial-thrust means capable of withstanding the pressure of the packed sliver.

The force acting upon four guide rollers 20 during the rotation of the pan is composed of a first force necessary to support the weight of the pan itself, a second force acting upon the lower surface of the pan to urge it upward caused by the expansion of sliver compacted in the sliver can, and a third force caused by unbalanced rotation.

However, it is easy to construct the pan so as to minimize its unbalance and also to have light weight, thus minimizing its rotating inertia.

When the top part shown in FIG. 3 and the bottom part shown in FIG. 4 are assembled as shown in FIG. 1, pins 5 and 6 at the lower end of the shaft 4 are loosely fitted in holes 24 and 25, respectively, of the pan 22. It should be noted that these pins and holes serve merely as a rotary motion transmitting device from the top part to the bottom part but do not restrict their supported positions. Thus their relative axial positions are flexible, i.e. there is freedom of relative axial movement but the rotation of the top part is positively transmitted to the bottom part so that they rotate in unison. With such construction, any force acting upon the top bearing 10 will not affect the bottom bearings 21. Similarly any force acting upon the bottom bearings will not affect the top bearing. Thus the top and bottom bearings operate quite independently to support the coiler-gear mechanism.

If the bottom bearings 21 were eliminated, and top and bottom parts were constructed as a unitary structure, then the top bearing 10 would be subjected to forces of various directions so that it would not operate satisfactorily at high speed. On the other hand, if the top bearing were eliminated, and if top and bottom parts were constructed as a unitary structure, the coiler gear mechanism would become unstable because it is driven by gears at a point considerably separated from the bottom bearing surfaces.

According to this invention, however, a coiler gear is divided into separate upper and bottom parts which are respectively provided with an anti-friction bearing, and the upper and lower parts are connected by a coupling means which functions solely to transmit rotary motion from the upper part to the lower part. Thus, this invention provides a novel coiler gear mechanism which can operate at high speed without any vibration and overheating of the bearings.

FIG. 5 shows another embodiment of this invention wherein a curved inclined tube 3 is substituted for the straight tube 3 shown in FIGS. 1 and 3. This curved guide tube 3 provides more efficient guiding action to the sliver in view of the centrifugal force imparted to the sliver at high speed and the deposit speed thereof.

In still another modification shown in FIGS. 6 and 7 the inclined guide tube 3 is mounted on the pan 22. It will be clear that such a modified construction can also operate satisfactorily.

While the invention has been explained by describing particular embodiments thereof, it will be apparent that improvements and modifications may be made without departing from the scope of the invention as defined in the appended claims.

What is claimed is:

1. In a coiling mechanism for depositing sliver in a sliver can, in combination, support means located above the mouth of the sliver can; an upper coiler member rotatably mounted on said support means and provided with a generally central inlet opening for said sliver; a lower coiler member rotatably mounted on said support means coaxial with said upper member and axially spaced therebelow; first bearing means journaling said upper member to said support means; second bearing means axially spaced from said first bearing means journaling said lower

member to said support means; coupling means interconnecting said members for joint rotation while permitting relative axial motion therebetween, said lower member being provided with a discharge opening outwardly of the axis of rotation of said members; guide means on one of said members interconnecting said openings for directing sliver from said inlet opening to said outlet opening; and drive means coupled with said upper member for rotating it about said axis.

2. In a coiling mechanism for depositing sliver in a sliver can, in combination, support means located above the mouth of the sliver can; an upper coiler member rotatably mounted on said support means and provided with a generally central inlet opening for said sliver; a disk-shaped lower coiler member rotatably mounted on said support means coaxial with said upper member and axially spaced therebelow; annular first bearing means journaling said upper member to said support means; second bearing means axially spaced from said first bearing means journaling said lower member to said support means, said second bearing means including a plurality of angularly spaced bearing rollers rotatable about respective axes parallel to the axis of said members in engagement with the periphery of said lower member; coupling means interconnecting said members for joint rotation while permitting relative axial motion therebetween, said lower member being provided with a discharge opening outwardly of the axis of rotation of said members; guide means on one of said members interconnecting said openings for directing sliver from said inlet opening to said outlet opening; and drive means coupled with said upper member for rotating it about said axis.

3. In a coiling mechanism for depositing sliver in a sliver can, in combination, support means located above the mouth of the sliver can; an upper coiler member rotatably mounted on said support means and provided with a generally central inlet opening for said sliver; a disk-shaped lower coiler member rotatably mounted on said support means coaxial with said upper member and axially spaced therebelow; annular first bearing means journaling said upper member to said support means; second bearing means axially spaced from said first bearing means journaling said lower member to said support means, said second bearing means including a plurality of angularly spaced bearing rollers rotatable about respective axes parallel to the axis of said members in engagement with the periphery of said lower member, said periphery being provided with a pair of spaced-apart flanges forming axial-thrust means for taking up the pressure of packed sliver in said can; coupling means interconnecting said members for joint rotation while permitting relative axial motion therebetween, said lower member being provided with a discharge opening outwardly of the axis of rotation of said members; guide means on one of said members interconnecting said openings for directing sliver from said inlet opening to said outlet opening; and drive means coupled with said upper member for rotating it about said axis.

4. In a coiling mechanism for depositing sliver in a sliver can, in combination, support means located above the mouth of the sliver can; an upper coiler member of relatively small diameter rotatably mounted on said support means and provided with a generally central inlet opening for said sliver; a lower coiler member of relatively large diameter rotatably mounted on said support means coaxial with said upper member and axially spaced therebelow; first bearing means journaling said upper member to said support means; second bearing means axially spaced from said first bearing means journaling said lower member to said support means; coupling means interconnecting said members for joint rotation while permitting relative axial motion therebetween, said lower member being provided with a discharge opening outwardly of the axis of rotation of said members; guide means on one of said members interconnecting said openings for directing sliver from said inlet opening to said

outlet opening; and a drive gear integral with said upper member for rotating it about said axis.

5. In a coiling mechanism for depositing sliver in a sliver can, in combination, support means located above the mouth of the sliver can; an upper coiler member of relatively small diameter rotatably mounted on said support means and provided with a generally central inlet opening for said sliver; a disk-shaped lower coiler member of relatively large diameter rotatably mounted on said support means coaxial with said upper member and axially spaced therebelow; annular first bearing means journaling said upper member to said support means; second bearing means axially spaced from said first bearing means journaling said lower member to said support means, said second bearing means including a plurality of angularly spaced bearing rollers rotatable about respective axes parallel to the axis of said members in engagement with the periphery of said lower member; coupling means interconnecting said members for joint rotation while permitting relative axial motion therebetween, said lower member being provided with a discharge opening outwardly of the axis of rotation of said members; guide means on one of said members interconnecting said openings for directing sliver from said inlet opening to said outlet opening, said upper coiler member being formed integrally with a drive gear for rotating said upper member about said axis, and drive means operatively coupled with said gear.

6. In a coiling mechanism for depositing sliver in a sliver can, in combination, support means located above the mouth of the sliver can; an upper coiler member rotatably mounted on said support means and provided with a generally central inlet opening for said sliver; a lower coiler member rotatably mounted on said support means coaxial with said upper member and axially spaced therebelow; first bearing means journaling said upper member to said support means; second bearing means axially spaced from said first bearing means journaling said lower member to said support means; coupling means interconnecting said members for joint rotation while permitting relative axial motion therebetween, said coupling means including a generally axially extending stem rigid with one of said members and interfitting formations on said stem and the other of said members, said lower member being provided with a discharge opening outwardly of the axis of rotation of said members; guide means on one of said members interconnecting said openings for directing sliver from said inlet opening to said outlet opening and drive means coupled with said upper member for rotating it about said axis.

7. In a coiling mechanism for depositing sliver in a sliver can, in combination, support means located above the mouth of the sliver can; an upper coiler member of relatively small diameter rotatably mounted on said support means and provided with a generally central inlet opening for said sliver; a disk-shaped lower coiler member of relatively large diameter rotatably mounted on said support means coaxial with said upper member and axially spaced therebelow; annular first bearing means journaling said upper member to said support means; second bearing means axially spaced from said first bearing means journaling said lower member to said support means, said second bearing means including a plurality of angularly spaced bearing rollers rotatable about respective axes parallel to the axis of said members in engagement with the periphery of said lower member, said periphery being provided with a pair of spaced-apart flanges forming axial-thrust means for taking up the pressure of packed sliver in said can; coupling means interconnecting said members for joint rotation while permitting relative axial motion therebetween, said coupling means including a generally axially extending stem rigid with one of said members and interfitting formations on said stem and the other of said members, said lower member being provided with a discharge opening out-

wardly of the axis of rotation of said members; guide means on one of said members interconnecting said openings for directing sliver from said inlet opening to said outlet opening, said upper coiler member being formed integrally with a drive gear for rotating said upper member about said axis; and drive means operatively coupled with said gear.
